United States Patent Office.

CHARLES DUMMELDINGER, OF CLEVELAND, OHIO.

Letters Patent No. 65,888, dated June 18, 1867.

IMPROVED ROOF FOR RAILROAD CARS.

The Schedule referred to in these Letters Patent and making part of the same.

TO ALL WHOM IT MAY CONCERN:

Be it known that I, CHARLES DUMMELDINGER, of Cleveland, in the county of Cuyahoga, and State of Ohio, have invented certain new and useful Improvements in Railroad Car Roofs; and I do hereby declare that the following is a full and complete description of the same, reference being had to the accompanying drawings, making a part of this specification, in which—

Figure 1 is a top view of the roof.

Figure 2 is a side view.

Figure 3 is a longitudinal section.

Like letters of reference refer to like parts in the different views.

This invention consists in covering the roofs of railroad cars with broad sheets of iron or tin, and so constructing the joints of the covering that they will not strain or break apart in consequence of the twisting and severe wrenching of the roof while the cars are running. The usual plan, when iron or tin is used for roofing, is to nail the sheets on the roof and making the joints by lapping, as is done on the roofs of ordinary buildings. These joints, in consequence of the great twisting and straining referred to, break away, and not unfrequently the material itself cracks, thereby causing the roof to leak. In order to obviate this difficulty, the sheets are put on as follows:

In fig. 3, A represents a section of a car roof, on which is laid a covering of two sheets of tin or iron, B B', the ends of which, instead of being made to lap on each other for the joint, are made to curl back over the sheet, forming a loop or tube, C, fig. 3, along the entire edge of the sheet, which in this case may be supposed to reach from the centre of the roof to the edge of the car, making one-half the width of the roof. It will be seen that the ends of the two sections of tin curve away from each other, and are made to touch only in a short vertical line, D, before curving; also, it will be observed that the ends of the sheets do not touch either the vertical line D or the top of the car, but simply approaching each other, leaving a short space between. These tubular joints are stayed at the centre with a band, E, passing around each tube and then nailed to the roof of the car under the sheets. They are still further stayed and secured to each other by a sheath, F, surrounding, locking and covering them, as shown in fig. 1, which figure shows the roof, or a longitudinal section of one-half of the roof, including one joint only, the number of joints being according to the size of the sheets employed for the roofing, and which are made to lap over the edges or eaves of the roof, and there nailed or otherwise properly secured. No nails being driven in any part of the sheeting, the ends of the sheath and joint, when completed in their attachments, are covered with cap, G, as a protection and finish.

It will be obvious that roofing put on with joints of this character cannot break, as the several sheets are not rigidly connected to each other by nailing or soldering; hence the joints will readily yield to any twisting or straining of the cars without displacement, breakage, or injury. In consequence of the end of the sheets not touching the vertical line of contact G, nor the top of the car, there can be no leakage by capillary action. Should there be water enough at any time lodge about the joint to enclose it, and being covered by the sheath, it cannot find its way in, though dashed against the joint in any direction, it being perfectly water-tight under all ordinary circumstances; hence by the use of this form of joint iron or tin may be used for roofing cars, instead of paper, canvas, or any combustible material ordinarily used, and therefore will secure greater safety against both fire and rain.

What I claim as my improvement, and desire to secure by Letters Patent, is—

The stay-bands E, tubular ends C, as arranged, in combination with the sheath F and car-roof A, for the purpose and in the manner set forth.

CHARLES DUMMELDINGER.
